UNITED STATES PATENT OFFICE

148,292

DESIGN FOR A ROAD ROLLER

Bryant Essick, Los Angeles, Calif.

Application October 10, 1945, Serial No. 122,708

Term of patent 14 years

(Cl. D14—3)

To all whom it may concern:

Be it known that I, Bryant Essick, a citizen of the United States, residing in the city of Los Angeles, county of Los Angeles, State of California, have invented a new, original, and ornamental Design for a Road Roller, of which the following is a specification, reference being had to the accompanying drawing, forming a part thereof.

Fig. 1 is a perspective view of the road roller taken to show the front and one side thereof, showing my new design, and Fig. 2 is a perspective view of the road roller taken to show the back and the other side thereof.

I claim:

The ornamental design for a road roller, as shown.

BRYANT ESSICK.
